Fig. 4

Fig. 3

FIGURE 1 is a perspective view of a microfilm reader showing my new design.

FIGURE 2 is a side view of the reader of FIGURE 1.

FIGURE 3 is a top plan view of the reader of FIGURE 2 showing especially the glass viewing surface of the reader.

FIGURE 4 is a front view of the reader of FIGURE 2.

The dominant features of my design reside in the portion shown in full lines and the rear portion of the microfilm reader is planar and unornamented.

I claim:

The ornamental design for a microfilm reader, as shown and described.
